UNITED STATES PATENT OFFICE

JOHN BRICKEN (NOW BY JUDICIAL CHANGE OF NAME JOHN GEORGE BEAVER), OF EAST ORANGE, NEW JERSEY, ASSIGNOR TO MONROE CALCULATING MACHINE COMPANY, OF ORANGE, NEW JERSEY, A CORPORATION OF DELAWARE

CALCULATING MACHINE

Application filed April 22, 1931. Serial No. 531,862.

This invention relates to calculating machines and more particularly to numeral wheel actuators therefor.

The principal object of the invention is to provide an actuator capable of positive action, of greater speed and more silent operation, whereby overthrow of the numeral wheel is impossible and the actuator and accumulator are always in mesh or locked condition.

Another object is to arrange the members to actuate in either direction of rotation.

These objects are effected by the provision of means to advance the driven member of the actuator a selected amount, moving the driving member into engagement with said driven member while in a position of rest and by releasing the same after the selected amount is accumulated and the driven member again brought to rest.

The invention consists in the novel construction and combination of parts, as set forth in the appended claims.

Fig. 1 is a top plan view of a machine embodying this invention.

Fig. 2 is a sectional view taken substantially on line 2—2, Fig. 1.

Fig. 3 is a sectional view taken substantially on line 3—3, Fig. 1.

Fig. 4 is a sectional view taken substantially on line 4—4, Fig. 2.

The invention is shown embodied in a machine in connection with known mechanism, to illustrate its application to calculating machines. Other forms of mechanism can be applied with similar effect. Additional numeral wheel groups or registers can be arranged at the rear of the machine by a duplication of the same parts associated with the same keyboard.

Referring to the drawings; a plurality of digit keys 15 are arranged in denominational rows, each row having a key for each significant digit, from 1 to 9 inclusive. Each key is provided with a spring 16 to maintain it in raised position. Each row of key stems are arranged in the path of a locking bail 17 which may hold any key in depressed position by engagement with notch 18. A zero key 19, in each row, is arranged to release

any depressed digit key. All other keys will upon depression release any key previously depressed in the same row, by means of rocking bail 17 riding on cam surface 20. Bar 21 extending from right to left of the machine in front of the 0 keys, is provided with pins 22 extending through slots of each 0 key stem 19. This bar 21 is rocked by key 23 to cancel any setting in the keyboard by depressing all of the 0 keys.

Each row of keys is mounted in a top plate 24 and a bottom plate 25, secured to the machine by an alternated arrangement of lugs 26 and 27 pressed into slots of partition plates 28 arranged between each denominational row of keys. The partition plates are spaced by a series of slotted blades 29, held in position by rod 30, through key holes in partition plates 28. The purpose of this arrangement is to assemble any number of rows in a complete machine, like parts being used for advantage in production.

Each denominational row has two rocking members 31 and 32 mounted upon plates 28 by pivot studs 33 and 34. Secured to the 75 rocking members by pivot studs 35 and 36 are bails 37 provided each with a series of lugs 38 on their upper edges, in graduated formation. Secured to bails 37 by pivoted links 39 and 40 are members 41, held against stops 42 by springs 43. Bails 37 are held in rearward position by slots 44 engaging pins 45 of levers 47 mounted upon plates 28 by pivot studs 48 and maintained in upward position by springs 49. The lower ends of rocking members 31 have pivot studs 50 supporting links 51 which have their rear ends secured by pivot pins 55 to blocks 52, free to slide in slots 53 of cam plates 54. Depression of any digit key causes member 41 to be moved downward, releasing 90 pin 45 from slot 44. Bail 37 becomes free to move forward, by the action of spring 56, for a distance determined by the graduated spacing of lug 38 in relation to the bottom of the depressed key stem 15, which serves as a stop. 95 Key stem 19 has no action on member 41 and will not release lock pin 45 holding bail 37 in 0 position.

Arranged in bearings on each side of the machine are shafts 57, on which are mounted 100

cam arms 58 and rocker plates 59. Rotation of double cam 60, used to provide for positive action, causes plates 59 to rock. Rocker plate 59 on the left side of machine is joined with rocker plate 59 on the right side of machine by through rods 61 forming a cradle for carrying the cam plates 54. Rotation of the driving elements of the machine causes cam plates 54 to be rocked about a fulcrum point located at center of stud 55, which as illustrated in Fig. 2, with selector set in 0 position, results in no motion of link 62, secured to pivot stud 55. Mounted on bearing 63, formed by pressing ears from plate 28, is a rocking member 64 connected to link 62 by pivot pin 65. Rocking member 64, engaging finger 66 in its slot 67, rocks finger 66 on pivot point 68. Rod 68, passing through the opening provided in the formation of bearing 63 and pivoting on the fingers of each denominational row, is rocked with shaft 69, also passing through each row; by connecting links 70. Shaft 69 is rocked by cam lever 71 in contact with double cam 72, used to provide for positive action. Cam 72 is rotated by shaft 73, driven by gears 74 and 75 from shaft 76. Bearing ring 77 is supported by ears pressed from plate 28 and forms a bearing for the rotating of squirrel cage actuator gear 78. Bearing ring 77 has an elongated slot 79 to allow for action of engaging finger 66, also a narrow slot 80 to form a bearing for locking finger 81. The front end of locking finger 81 is pivoted on rod 68 independently of finger 66 and, being guided in bearing 80, moves radially of gear 78, in the movement of shaft 69. By following this motion it can now be seen that the setting of an amount upon the keyboard causes pivot point 55 to move forward in slot 53 of cam plate 54; to an extent sufficient to cause engaging finger 66 to import the desired degree of movement to gear 78 when cam plate 54 is rocked clockwise as viewed in Fig. 2. The camming movement is so arranged that pivot point 68 is rocked forward to engage finger 66 between teeth of gear 78 and release locking finger 81 when cam plate 54 is in the extreme downward position and at a point of dwelling. After finger 66 is rocked upward to rotate gear 78, clockwise, the selected amount, pivot point 68 is rocked rearward, engaging the lock and releasing finger 66, which is returned idly to normal position. Upon reversal of the machine the driving elements will rotate gear 78 counter-clockwise, by engaging finger 66 with gear 78 in the extreme upward position of the finger, the down stroke being now active, instead of the up stroke. Rocking member 31 is locked in selected position, with rod 82 engaging the teeth thereof, when the actuator is in motion. Rod 82, connecting with levers 83, is rocked from shaft 84, by the action of cam 85, lever 86 and spring 87.

Rod 88 which is arranged in front of rocking members 31 and, sliding in slot 89, returns the selector to 0 position at the end of each cycle, by the action of link 90 pivotally connected to link 91, which is rocked by shaft 92; arranged to rock from cam 93 and compound levers 94 and 95.

Well known planetary gear carry mechanism is applied to the numeral wheels and driven by intermediate gears 96. Gear 97, rotating gears of the planetary system advances the numeral wheel and also a single tooth gear 98. At the carry position, single tooth gear 98 rotates gear 99, advancing gear 100, fast to the same hub. Gear 101 of next higher order, encasing the planetary intermediate gears, is advanced by gear 100 and rotates the numeral wheel an additional one tenth of a revolution.

Motor drive mechanism arranged to drive shaft 76 is provided and is adapted to be called into action by the plus and minus keys. This arrangement being well known, no special description thereof is included herein.

Likewise, clearing of the numeral wheels and shifting of the numeral wheel carriage may be effected by any of the known mechanical means.

I claim:

1. In a calculating machine having numeral wheels; actuators therefor comprising each a driven gear, two interconnected pawls, means for moving said pawls alternately into contact with said gear, and means for advancing one of said pawls varying distances to advance said gear differentially.

2. In a calculating machine having numeral wheels; actuators therefor comprising each an internal gear, an oscillatory arm mounted within the circumference of said gear, two pawls mounted upon said arm and movable thereby alternately into contact with said gear, means for moving one of said pawls pivotally, and means for varying the pivotal movement of said pawl.

Signed at Orange in the county of Essex and State of New Jersey, this 30th day of March, A. D. 1931.

JOHN BRICKEN.
